UNITED STATES PATENT OFFICE.

JOSEPH MURPHY, OF NEW YORK, N. Y.

DESIGN FOR A CLOTHES-LINE FASTENER.

44,730.

Specification for Design.

Patented Oct. 14, 1913.

Application filed July 9, 1913. Serial No. 778,222. Term of patent 7 years.

To all whom it may concern:

Be it known that I, JOSEPH MURPHY, a subject of the King of Great Britain, residing at the city of New York, borough of Brooklyn, in the county of Kings and State of New York, have invented a new, original, and ornamental Design for a Clothes-Line Fastener, of which the following is a specification, reference being had to the accompanying drawing, forming part thereof, in which—

Figure 1 is a front view in perspective of a clothes line fastener, showing my new design; Fig. 2 is a rear view; and Fig. 3 is a cross section on the line 3—3 of Fig. 2 indicating the surface configuration.

I claim:

The ornamental design for a clothes line fastener, as shown.

JOSEPH MURPHY.
